Joseph P. Levy

UNITED STATES PATENT OFFICE.

ARTHUR N. BACHRACH, OF NEW YORK, N. Y., ASSIGNOR TO SAMUEL L. BACHRACH, OF NEW YORK, N. Y.

NECKTIE.

1,163,308.

Specification of Letters Patent.

Patented Dec. 7, 1915.

Application filed November 7, 1914. Serial No. 870,779.

To all whom it may concern:

Be it known that I, ARTHUR N. BACHRACH, a citizen of the United States, residing in the city, county, and State of New York, and whose post-office address is 251 Fifth avenue, in said city, have invented certain new and useful Improvements in Neckties, of which the following is a specification.

My invention relates to neckwear and its 10 special object is to provide a form of neck tie, of novel shape and construction and which, when tied in place, will produce the effect of a double wing and a contrast of colors imposed one upon the other.

15 My invention resides in the novel construction or article of manufacture and combination of parts hereinafter described and more fully set forth in the claims appended hereto.

In the drawing forming part of this specification, Figure 1 is a rear elevation or face view of the tie embodying my improvements; Fig. 2 is a like view of the front face of the tie; Fig. 3 is an enlarged edge view of one 25 end of the tie; Fig. 4 is a sectional elevation of Fig. 3 on the line 4—4 of Fig. 1; Fig. 5 is an end view of Fig. 1 somewhat enlarged; and Fig. 6 is a front elevation showing the aspect of the neck tie embodying my improvements when tied in the conventional 30 manner.

I have illustrated my improvements in connection with the particular type of a neck tie commonly called a string tie, although it will be manifest that the improvements can be used in other relations. In ties 35 of this character, the effort has been to produce a widened or "bat wing" effect at the ends, so that the majority of ties of this character have ends laterally enlarged. My 40 improvements, however, may be embodied in a tie of this character, where the ends are of the same lateral dimension as the band or body of the tie and even where they are smaller.

45 In the tie shown, 1 indicates a neck band and 2 indicates generically the end of the tie. Instead of forming a tie with a single end, I produce two (or even more) ends or tabs, to form the wing or apron of the tie.

These tabs are preferably widened portions, 50 as compared with the neck band 1. I prefer, in order to get the double tie or varicolored effect, which may be had with my improved tie when the same is finally formed about the neck of the wearer, as shown in 55 Fig. 6, to make one of the tabs or wings 3 a little shorter than the other, and I still further prefer that the shorter of the wings 3, be placed upon the inside, so that when the same is tied in the conventional manner, the shorter wings 3 will be superposed upon the longer ones 4. If the color or design of the shorter wings is made different from that of the longer wings, various contrasting effects can be produced. The shortened wings 3 also produce the novel effect, 60 as shown in Fig. 6, of a double tie.

While any of the conventional methods of manufacture may be employed in making this tie, I prefer that shown herein, in which 70 the band portion 1 is made up of two pieces of material, the ends of which are used to form the tabs or wings 3 and 4. The inner face of the tabs is formed of a single strip of material 5, which extends between the tips 75 of the wings, but which is preferably not secured to the band portion of the tie, except by the interior stitching 6, so that when the ends 3 and 4 are opened out, as shown in Fig. 5, a single piece of material inside 80 the wings will be presented. The rows of stitching 6 are formed in the usual or conventional manner. Of course, it is obvious that the tie and any of its parts can be built up of a number of pieces of material with- 85 out departing from my invention.

While I have shown my invention in a specific form, and in connection with a specific type of tie, it is manifest that it may be variously embodied, without departing 90 from the spirit of my invention.

I claim:

1. In a necktie, the combination with a band or body portion, a plurality of tabs or wings extending from each end of the 95 body portion, and forming tying portions of the necktie.

2. In a necktie, the combination with a

band or body portion, a pair of tabs or wings extending from each end of the body portion, the wings being wider than the band or body portion, one of the wings on each end of the band or body portion being shorter than the other wings, all of said wings forming tying portions of the necktie.

Copies of this patent may be obtained for five cents each, by addressing the "Commissioner of Patents, Washington, D. C."

Signed at the city, county and State of New York, this 26th day of October, 1914.

A. N. BACHRACH.
